TIMING LIGHT

Stephen E. Taylor, 906 Groton Drive, Burbank, Calif.

Filed Oct. 5, 1964, Ser. No. 82,039

Term of patent 14 years

(Cl. D52—1)

Fig. 1.

Fig. 2.

Fig. 3.

Fig. 4. Fig. 5.

FIG. 1 is an elevational view of one of the sides of a timing light showing my new design;

FIG. 2 is a top plan view;

FIG. 3 is a bottom plan view;

FIG. 4 is a front end view; and

FIG. 5 is a rear end view of the same.

The undisclosed sides of the timing light is substantially the same in appearance as the side shown.

The dominant features of my design reside in the portion shown in full lines.

I claim:

The ornamental design for a timing light, as shown and described.
